CRANKPIN GRINDING APPARATUS

Joseph A. Sills, St. Charles, Ill.

Application November 12, 1952, Serial No. 320,029

5 Claims. (Cl. 51—184.2)

1

The present invention relates to apparatus for grinding and refinishing the crankpin on a crankshaft of an internal combustion engine, or the like, while the crankshaft is in its normal position supported by its main bearings in the engine block.

Grinding and refinishing apparatus that have been proposed heretofore for the purpose noted have not met with any substantial commercial success due primarily to the complicated and expensive character of the elements involved and to the difficulty of obtaining proper alignment between the crankpin undergoing the operation and its associated cylinder in the engine block.

Accordingly it is a general object of the present invention to provide an improved apparatus for grinding and refinishing a crankpin as previously noted that positively insures proper alignment between the crankpin and its cylinder in the engine block.

Another object of the invention is to provide an improved apparatus for grinding and refinishing a crankpin as previously noted while the crankpin undergoing the operation is connected by a connecting rod to its piston arranged in its cylinder in the engine block, whereby the guided reciprocatory movement of the connecting rod establishes proper alignment between the crankpin and its cylinder as the operation proceeds.

A further object of the invention is to provide exceedingly simple apparatus for grinding and refinishing a crankpin on a crankshaft while the crankshaft is supported by its main bearings in an engine block and while the crankpin is operatively connected by a connecting rod to its piston arranged in its cylinder in the block.

Further features of the invention pertain to the particular arrangement of the elements of the apparatus, whereby the above-outlined and additional operating features thereof are attained.

The invention, both as to its organization and method of operation, together with further objects and advantages thereof, will best be understood by reference to the following specification taken in connection with the accompanying drawing, in which:

Figure 1 is an upstanding lateral sectional view of an internal combustion engine of the L-head type and incorporating grinding and refinishing apparatus embodying the present invention;

Fig. 2 is an enlarged top view of the upper bearing member and upper grinding element incorporated in the apparatus shown in Fig. 1;

2

Fig. 3 is an enlarged side view of the parts shown in Fig. 2;

Fig. 4 is an enlarged bottom view of the lower cap and lower bearing member and lower grinding element incorporated in the apparatus shown in Fig. 1;

Fig. 5 is an enlarged top view of the parts shown in Fig. 4; and

Fig. 6 is an enlarged side view, partly broken away, of the parts shown in Figs. 4 and 5.

Referring now to Fig. 1 of the drawing, there is illustrated a conventional internal combustion engine 10 of the L-head type (Plymouth, 1939) including a block 11, a head 12 detachably secured to the top of the block 11, and an oilpan 13 detachably secured to the bottom of the block 11, the lower portion of block 11 and the oilpan 13 cooperating to define a crankcase 14 housing a crankshaft 15 mounted for rotation upon main bearings, not shown. The block 11 is provided with six cylinders in which six pistons are respectively arranged, one of the cylinders and one of the pistons being respectively indicated at 16 and 17. The crankshaft 15 is provided with six crankpins respectively aligned with the six cylinders, the crankpin aligned with the cylinder 16 being illustrated at 18. The piston 17 and the crankpin 18 are interconnected by a connecting rod 19, the upper or piston end of the connecting rod 19 being directly connected to the piston 17 by a wristpin 20 and the lower or crank end of the connecting rod 19 terminating in a flange 21 that normally carries an upper bearing member, not shown. Also a bearing cap, not shown, is provided that carries a lower bearing member, not shown, the bearing cap being detachably secured to the flange 21 by bolts 22, whereby the upper and lower bearing members engage the opposite sides of the crankpin 18 embraced thereby. The head 12 is provided with six domes 23, etc. respectively cooperating with the upper ends of the six cylinders 16, etc.; as well as six intake poppet valves 24, etc., and six exhaust poppet valves, not shown, that respectively control the cycles of the pistons 17, etc. Finally the head 12 has six threaded holes 25, etc. therein that respectively receive six spark plugs, not shown, that are incorporated in the ignition system of the engine 10.

Now in the event it becomes necessary to regrind or refinish the crankpin 18, the oilpan 13 is removed from the bottom of the block 11, followed by the removal of the bearing cap and carried lower bearing member, not shown, and by the removal of the upper bearing member, not

shown, from the flange 21. The grinding apparatus, illustrated generally at 30, is then assembled upon the crankpin 18 and the flange 21; and thereafter the grinding and refinishing operation is carried out, as explained more fully hereinafter, by rotating the crankshaft 15, while the crankshaft 15 is supported by its main bearings, not shown, in the block 11, and while the crankpin 18 is connected by the connecting rod 19 to the piston 17.

More particularly, the apparatus 30 comprises an upper assembly 31, shown in Figs. 2 and 3, and a lower assembly 32, shown in Figs. 4 to 6, inclusive. The assembly 31 essentially comprises an upper substantially semi-cylindrical bearing member 33 terminating in two laterally spaced-apart and outwardly and oppositely directed flanges 34 having bolt holes 35 formed therein, and carrying two upper grinding elements or pads 36 containing carborundum or other grinding compound. The assembly 32 essentially comprises a lower bearing cap 37 terminating in two laterally spaced-apart bosses 38 having bolt holes 39 formed therein. Also the cap 37 carries a substantially semi-cylindrical lower bearing member 40 arranged in two laterally spaced-apart sections and essentially formed of babbitt or other bearing material, as well as a centrally disposed grinding shoe 41 carrying a lower grinding element or pad 42 containing carborundum or other grinding compound. More particularly, the central portion of the cap 37 has a longitudinally extending slot 43 formed therein that terminates into a wider longitudinally extending slot 44 formed therein, the sides of the slot 44 being disposed adjacent to the inner ends of the two sections of the bearing member 40; and the grinding shoe 41 being substantially T-shaped in cross-section, including a stem 45 fitting into the slot 43 and a head 46 fitting into the slot 44. Further two laterally spaced apart threaded openings are formed in the cap 37 that receive two set screws 47 that project into two laterally spaced apart holes 48 formed in the stem 45 of the grinding shoe 41, the holes 48 also receiving resilient coil springs 49 surrounding the inner ends of the set screws 47. Thus it will be understood that the springs 49 resiliently bias the grinding shoe 41 inwardly toward the center of the cap 37, while the set screws 47 accommodate adjustment of the angle between the opposite ends of the grinding shoe 41 and the longitudinal centerline of the cap 37.

In assembling the apparatus 30 upon the crankpin 18 and the flange 21, the assembly 31 is placed in the flange 21 (instead of the usual upper bearing member), and the assembly 32 is secured to the flange 21 by the bolts 22 (instead of the usual lower bearing cap). Accordingly, at this time the upper grinding pads 36, as well as the lower grinding pad 42, directly engage the exterior surface of the crankpin 18; and the bearing cap 37 secures the assemblies 31 and 32 to the crankpin 18 and to the flange 21; whereby the apparatus 30, as a whole, is maintained in alignment with respect to the cylinder 16 associated with the crankpin 18. Moreover the springs 49 urge the grinding pad 42 upwardly into firm engagement with the adjacent surface of the crankpin 18; whereby a grinding pressure is maintained between the crankpin 18 and the grinding pads 36 and 42. At this time, the crankshaft 15 is rotated; whereby a grinding action is produced by the grinding elements 36 and 42 upon the exterior surface of the crank-

pin 18; and the piston 17 is reciprocated in the cylinder 16 by virtue of the operative connection, including the connecting rod 19, between the crankpin 18 and the piston 17. The guided reciprocatory movement of the piston 17 in the cylinder 16 maintains through the connecting rod 19 proper alignment of the apparatus 30 so that the reground or refinished surface of the crankpin 18 is in proper alignment with respect to the cylinder 16.

In passing, it is noted that the crankshaft 15 may be rotated by hand or in any suitable manner, such, for example, as by the starter motor normally associated with the engine 10. On the other hand, the spark plug normally associated with the threaded hole 25 in the dome 23 may be removed, and the engine 10 may be run employing the other five pistons under its own power. In any case, the crankshaft 15 is rotated for the required relatively few revolutions so as to bring about the required and desired grinding action by the apparatus 30 upon the crankpin 18. Ordinarily it is not necessary to assemble the oilpan 13 upon the bottom of the block 11 as there is no damage to the moving parts during the short time interval required in grinding the crankpin 18.

In the foregoing description of the grinding the crankpin 18 employing the apparatus 30, it was assumed that the upper bearing member normally carried by the flange 21 of the connecting rod 19 is readily removable therefrom, which is the case in the usual Chrysler engine (Chrysler, DeSoto and Plymouth). However, in some General Motors engines (Buick, Oldsmobile, etc.), the upper bearing member is directly babbitted or cast in place in the flange 21 of the connecting rod 19; whereby in this case, it is necessary to provide in conjunction with the apparatus 30, a connecting rod for the particular engine that has the upper bearing element removed therefrom. In this peculiar case, the regular connecting rod 19 is detached from the piston 17 at the wristpin 20 and the alternative connecting rod mentioned is substituted so that the substituted connecting rod may readily receive the assembly 31, in the manner previously explained.

In connection with the operation of the apparatus 30, it is emphasized that the arrangement of the set screws 47 accommodates adjustment of the angle between the opposite ends of the grinding shoe 41 and the longitudinal centerline of the crankpin 18 so that an original and undesired taper or cone-shape in the outer surface of the crankpin 18 may be removed or eliminated therefrom in the operation of the apparatus 30. Specifically in this case, the set screw 47 adjacent to the larger end of the crankpin 18 is set tighter than the other set screw 47 adjacent to the smaller end of the crankpin 18 so that the grinding pressure is greater at the larger end of the crankpin 18 in order preferably to grind the larger end of the crankpin 18 so as to remove the undesired taper mentioned.

In view of the foregoing, it is apparent that there has been provided an improved apparatus for grinding or refinishing the crankpin on a crankshaft while the crankshaft is supported in its main bearings in the engine block and while the crankpin undergoing the operation is operatively connected to its piston arranged in its cylinder in the engine block; that is of exceedingly simple construction and arrangement involving only a few quite simple parts. Further,

it will be appreciated that the apparatus is very advantageous as the mere rotation of the crank-shaft positively insures that the reground or re-finished surface on the crankpin undergoing the operation is positively in alignment with its associated cylinder by virtue of the fact that the guided reciprocatory movement of the connected connecting rod compels the alignment mentioned.

While there has been described what is at present considered to be the preferred embodiment of the invention, it will be understood that various modifications may be made therein, and it is intended to cover in the appended claims all such modifications as fall within the true spirit and scope of the invention.

What is claimed is:

1. Apparatus for grinding the crankpin on a crankshaft while said crankshaft is supported by its main bearings in an engine block and while said crankpin is operatively connected by a connecting rod to its piston arranged in its cylinder in said block; said apparatus comprising a first bearing member carried by the crank end of said connecting rod, a cap, a second bearing member carried by said cap and having a longitudinally extending slot formed therein, an elongated grinding element arranged in said slot, means for detachably securing said cap to the crank end of said connecting rod and for clamping said crankpin between said bearing members with said grinding element in engagement with said crankpin, resilient means arranged in said slot between said cap and said grinding element for biasing said grinding element toward said crankpin, the clamping action between the crank end of said connecting rod and said cap producing a grinding pressure between said grinding element and said crankpin and securing the crank end of said connecting rod to said crankpin so that the normal cooperation between said piston and said cylinder establishes proper align-

ment between said crankpin and said cylinder as the grinding operation is carried out by rotation of said crankshaft, and means for adjusting the relative positions of the opposite ends of said grinding element with respect to the longitudinal centerline of said crankpin.

5 2. The apparatus set forth in claim 1, wherein said adjusting means essentially comprises two set screws arranged in two longitudinally spaced-apart threaded holes formed in said cap and extending into the opposite ends of said slot into respective engagements with the opposite ends of said grinding element.

10 3. The apparatus set forth in claim 2, wherein said resilient means arranged in said slot between said cap and said grinding element for biasing said grinding element toward said crankpin consists essentially of two coil springs respectively surrounding said two set screws.

15 4. The apparatus set forth in claim 1, and further comprising a grinding pad carried by said first bearing member and arranged in grinding relation with said crankpin.

20 5. The apparatus set forth in claim 1, and further comprising two spaced-apart grinding pads carried by said first bearing member and both arranged in grinding relation with said crankpin, whereby three spaced-apart grinding actions upon said crankpin are carried out by the rotation of said crankshaft.
